UNITED STATES PATENT OFFICE.

FREDERICK F. HODGKINS, OF EAST BOSTON, MASSACHUSETTS.

INFLATABLE COAT.

932,608.

Specification of Letters Patent. Patented Aug. 31, 1909.

Application filed May 6, 1909. Serial No. 494,414.

To all whom it may concern:

Be it known that I, FREDERICK F. HODGKINS, a citizen of the United States, and resident of East Boston, in the county of Suffolk and State of Massachusetts, have invented new and useful Improvements in Inflatable Coats, of which the following is a specification.

My invention relates to the construction of waterproof garments such as are used by seamen and fishermen and consists in improvements whereby the ordinary waterproof coat such as the oilskin garments now almost universally used may be simply, cheaply and effectively provided with an inflatable chamber which not only serves in emergency as a life preserver but also improves the comfort and efficiency of the garment in the service of the ordinary uses to which it is adapted.

I am aware that very many contrivances in the shape of inflatable life preserving garments or attachments thereto have heretofore been made and patented; so far as I am aware, however, such garments or the inflatable adjuncts thereto have been so constructed as more or less to detract from the ordinary utility of the garments themselves and have involved special contrivances which make the garment too expensive to be available to the very class of people who more than others are likely to require a life preserver. It is, I believe, a significant circumstance that sailors and fishermen at the present day never employ any such life preserving garments as have been contrived and patented; I believe the reasons to be first that the inflatable attachments of such garments as have heretofore been constructed or suggested are inconvenient, heavy, necessarily incommod the wearer, even when deflated; and, second, are expensive. Apparently, the inventors of such devices have supposed that a perfectly air and waterproof chamber is necessary for the purpose and that, therefore, special attachments or specially contrived garments are indispensable.

My invention herein described, in contrast to the life preserving garments with which I am acquainted, calls for no special or expensive addition or attachment, is applicable to the cheap universally used waterproof garments now in vogue, and adds so little to the expense of constructing such garments, that the cost of production or the selling

price thereof need not be materially increased.

In the drawings hereto annexed which illustrate my invention,—Figure 1 is a view of the back of an ordinary oilskin coat embodying my improvement; and Fig. 2 is a view of the front thereof.

The so-called oilskin coat as now constructed is composed of the outer portion or coat O and an inner portion or lining I, the lining being continuous throughout the inside of the coat, both as to body and sleeves. Both these essential portions are composed of cotton cloth and after being stitched, are treated with boiled linseed-oil and dried. These coats for all practical purposes are waterproof, although they are by no means so impervious as rubber or rubber-coated cloth, and for this reason, as well as on account of the cheapness of such garments, they are preferred to rubber clothing, being lighter and on the whole better ventilated.

In applying my improvement to the construction of garments of the character above described, I attach to the lining thereof at a convenient place in the breast portion, a flexible rubber tube as T and provide this rubber tube with a simple constricting clip composed of spring metal as at T'. Such clips are an ordinary article of commerce and are easily attachable to a rubber tube. I then form an endless line of stitching which passes through the outer coat O and the lining I joining the two and forming a chamber with which the tube T communicates. This line of stitches crosses the back of the garment between the shoulders at s' (Fig. 1) then downward on either side at s² under the arm size, upward at the front of the garment at s³, to a point opposite or nearly opposite the rear line of stitches s', across at s⁴, then downward adjacent to the button flap at s⁵ and entirely around the back at the line s⁶. When the coat has been so prepared, it is oiled and dried in the usual manner, the oiling taking effect upon the stitches made as aforesaid. The stitching above described may be applied to a coat after oiling and serve substantially as well as when the stitching is done before oiling, though in such case the stitching had better be made with an oiled or waxed thread. Preferably, the stitching is a double thread lock stitch and the stitching when finished

should form a continuous or endless line. This may be effectively accomplished by causing the line of stitches to overlap at the beginning and end. When formed as above 5 described, the chamber inclosed between the upper coat O and lining I is not absolutely air tight either in respect to the cloth walls thereof or the bordering line of stitches; it is however, sufficiently air tight for all 10 practical purposes and will remain inflated without reinflation for a considerable time. The very circumstance that there is a slight leakage, I consider to be an advantage rather than a detriment. Clothing of this kind is 15 worn by sailors and fishermen in wet weather and after very long exposure to rain or sleet the garment as usually constructed will be found to be damp on the inside. The inflatable chamber above described when 20 very slightly inflated separates a considerable portion of the outer coat O from the lining I and makes the former serve with the latter somewhat as the flap of a tent to the inner part thereof, so that the coat will 25 remain dry over a large part of its inner surface. The slow escape of air through the cloth outward effectively prevents the entrance of water. By providing only a single inflatable chamber of the character described, even when this is filled or partially 30 filled with air, it will not incommod the wearer, since any pressure of the arms upon the sides will instantly displace the air to other portions of the chamber.

35 In practical use the manner to be recommended is for the wearer to inflate the chamber very slightly so as to secure all the advantages of protection from moisture and from the cold while the coat is not so fully inflated as to make it awkward. If by chance the wearer falls overboard this small 40 quantity of air in the chamber will suffice to keep his head above water, making it easy for him to complete the full inflation by 45 blowing through the tube T.

The formation of the endless line of stitches which makes the inflatable chamber is the work of a moment only, does not in

any degree modify the practical construction of the garment, and is so inexpensive 50 that such waterproof coats with this improvement applied may be sold to sailors and fishermen at no more than the ordinary price, or at the most, at a price only a few cents in advance of that now charged, and 55 thus an effective life preserving garment may be supplied to people who need it most and who are the least able to purchase expensive contrivances of the kind while the garment itself is still as convenient for ordinary purposes as though there were no inflatable chamber incorporated therewith.

I have shown the inflatable chamber as occupying a conveniently large portion of the garment; if desired, a larger chamber 65 may readily be made by running the endless line of stitches so as to include as much of the garment as the maker pleases.

What I claim and desire to secure by Letters Patent is:

1. The combination of a coat and lining therefor, both composed of waterproof textile material, the lining and coat joined by an endless line of stitches, which form a closed receptacle between the coat and lining, and means for inflating said receptacle. 75

2. The combination of a coat and lining therefor, both composed of waterproof textile material, the lining and coat joined by an endless line of stitches, passing across the 80 back from shoulder to shoulder, under a sleeve and upward toward the collar, thence downward parallel to the button-flap, around the back of the coat to the front at the other flap, thence upward toward the collar, thence 85 downward and to the rear below the other sleeve, and thence upward, forming a closed receptacle between the coat and lining, and means for inflating said receptacle.

Signed by me at Boston, Massachusetts, 90 this fifth day of May 1909.

FREDERICK F. HODGKINS.
